is laid on the ends of feet 4 and 5 a piece 8 heated to a temperature sufficient to bring the feet to a plastic or flowing state on at least a part of their length. There is simultaneously exerted an axial pressure on the extremity of the feet by means of piece 8 in order to make the liquified material occupy completely openings 2 and 3 as shown on FIGURE 2. The attachment of the sign is obtained after cooling owing to the adherence of the solidified plastic material against the walls of openings 2 and 3. In effect these walls present minuscule roughened areas resulting from piercing thereof to which the liquified material becomes rigidly attached through the influence of the pressure exerted by tool 8.

It is evident that sign 6 can be secured by means of a single foot shown on FIGURE 3. In this modification of the invention the foot can be advantageously given a cross-sectional shape other than circular, for example, square as shown on FIGURE 4. The shape of the cross-section will permit to exactly position the time sign, the foot being introduced in an opening 10 having a corresponding shape, and provided in the dial plate. The attachment will take place in the same manner as in the first embodiment.

The foot can also be given a circular cross-section as shown in FIGURE 5 by positioning the sign in an imprint presenting the negative of the back of the dial or by any other means.

Another modification resides in the flaring of the openings 2 and 3 so as to form a housing or lodging 7 in which the plastified materials spread under the pressure of member 8.

FIGURES 8 and 9 show by way of example a device for carrying out this process wherein members 8 are integral with a common support 11 containing electrical resistance 12.

The source of heat naturally can be of another nature, ultra-sonic or chemical for example.

The process according to the invention is not limited to the securing of time signs on finished or unfinished dials, but can also be used for attaching any other elements on the dials, such as a ring, segment, circle, symbol, trademark or other decorative element.

Naturally many types of plastic materials can be used in the practice of the claimed invention and the temperatures at which the process will be carried out will depend on the softening point of these plastic materials, all of which are well known to those skilled in the art. As examples of suitable plastic materials, there may be used polystyrene, polyethylene, epoxy resins, and in general any hard plastic resinous materials having an appreciable resistance to wear and which can be softened at a reasonably low temperature. Naturally the plastic material constituting the time indicia can be metallized or can have incorporated therein various colouring agents so as to give them the desired colour.

What is claimed is:

1. A timepiece dial comprising a dial plate of a given thickness and having a plurality of openings therein, said openings having rugosities in the walls thereof, said openings being positioned in areas where time signs are desired, a plastic time sign sitting over each of said openings, said time sign having at least one projection sitting in said opening and fused to said rugosities in said opening.

2. A timepiece dial according to claim 1, wherein said projection, before being fused to said dial, has a length greater than said thickness of said dial.

3. Dial according to claim 1, wherein said openings are flared outwardly toward the back of said plate.

4. Dial according to claim 1, wherein said time signs are made of a plastic material selected from the group polystyrene, polyethylene and epoxy resins.

ABSTRACT OF THE DISCLOSURE

A watch dial having time signs affixed thereto, the signs having at least one projecting foot the length of which slightly exceeds the thickness of the dial plate. The foot, composed of a plastic material, passes through an opening in the dial plate and upon heating will be fused to the rugosities in the opening.

Already known are timepiece dials of this type in which the time indicia are obtained by injecting liquid plastic material directly on the plate of the dial which is placed in a mould. The tooling necessary for carrying out such a process is costly and a new mould must be especially made for each type of dial. Moreover, the carrying out of such a process is delicate, especially when it is desired to make curved dials. Actually in order to obtain good results, it is necessary that the upper surface of the dial adhere perfectly to the mould. It is known however that the tolerances of curvature of dials are rather wide.

It has also been proposed to glue signs in relief on a dial. If the sign is glued on the surface of the dials, the glue may overrun the periphery of the indicia. To avoid this, the time sign has been provided with a foot which has been introduced in an opening of the dial which opens towards the back side thereof thus providing a lodging around the extremity of the foot, around which is run a varnish. This process when used with a metallic foot necessitates the elimination of the part of the varnish overflowing the lodging and owing to this requires additional manipulations.

Other processes recommend the securing of time signs by coalescing, by ultra-sonic welding. These have been utilized with success only in the case of plastic time signs in relief on a plate of plastic material.

The accompanying drawings represent by way of example various modifications of the present process.

FIGURE 1 is a cross-sectional view of a dial with a time sign positioned thereon but not secured thereto.

FIGURE 2 is a cross-sectional view of the dial with the time sign secured.

FIGURE 3 is a cross-sectional view of a second modification of the invention taken along lines III—III of FIGURES 4 and 5.

FIGURES 4 and 5 are side views of the back of the dial in a second embodiment of the invention.

FIGURE 6 is a cross-sectional view of another modification.

FIGURE 7 is a schematic view of apparatus intended for use in the attaching of time indicia according to the invention.

FIGURE 8 is a cross-sectional view taken along VIII—VIII of FIGURE 7.

FIGURE 1 shows a dial plate 1 pierced by openings 2 and 3 through which pass the feet 4 and 5 of a sign in relief 6. The length of the feet exceeds slightly the thickness of the dial plate 1.

After having placed all the signs on the dial plate, there

5. Dial according to claim 4, wherein said time signs
are metallized. 1,436,058 3/1966 France.
74,040 1/1917 Switzerland.
6. Dial according to claim 4, wherein said time signs
contain coloring agents. 320,002 4/1957 Switzerland.
340,448 9/1959 Switzerland.
353,682 5/1961 Switzerland.
